UNITED STATES PATENT OFFICE

CHARLES ALBERT BESCH, OF LA CROSSE, WISCONSIN

REGISTER

Application filed March 31, 1928. Serial No. 266,358.

This invention relates to registers and more particularly to valve controlled heat conducting registers designed primarily to be attached to the walls of buildings and connected with hot air heating systems, but it is to be understood that a register in accordance with this invention may be employed for any purposes wherein it is found applicable, and the invention has for its object to provide in a manner as hereinafter set forth a register for humidifying the heated air emitted therefrom.

Another object of the invention is to provide in a manner as hereinafter set forth for utilizing the damper or valve of the register as a receptacle for the humidifying medium, and to further provide a moisture dispersing element whose activity is accelerated by the heat.

Further objects of the invention are to provide in a manner as hereinafter set forth a device of the character described, which is strong, durable, and compact, highly efficient for its intended purposes without detracting from the appearance of the building, simple in its operation and construction, adapted for connection to any heating system, easily installed and comparatively inexpensive to manufacture.

With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modifications may be resorted to which fall within the scope of the invention as claimed.

In the drawings wherein like reference characters denote corresponding parts throughout the several views:-

Figure 1 is a side elevation of the register in accordance with this invention.

Figure 2 is a section on line 2—2 of Figure 1, looking in the direction of the arrows.

Figure 3 is a section on line 3—3 of Figure 2, looking in the direction of the arrows.

A wall register in accordance with this invention is made of metal of suitable thick-

ness and may be decorated on its outer faces in accordance with the color scheme desired. Referring to the drawings in detail a substantially rectangular metallic casing or hood is indicated at 5, having a top, rear side wall and both end walls closed, and having a front side wall open the major portion of its area for connection and communication with the register frame, and further having an open bottom adapted for connection with a conductor pipe or hot air flue not shown in the drawings.

The register frame is pressed out of a single piece of metal of suitable thickness. The frame includes a rearwardly directed U-shaped flange 6 extending from the triangular shaped sides 6', and further includes a beveled front 7 diverging from the top of the flange and merging with the triangular side walls, which front has a rectangular shaped central opening coextensive with the major portion of the area.

The hood includes a flange 8 turned at right angles to the walls surrounding the opening in the hood, lapping over edge 9 and abutting the beveled front 7 adjacent the edge 9 which surrounds the top and two sides of the central opening in the frame, while the bottom edge 10 of the central opening is secured in the lap 11 formed by folding a portion of the wall adjacent the bottom edge of the opening in the hood, thereby securing the register frame to the hood so that the opening in the frame communicates with the opening in the front side wall of the hood.

Around the outer edge of the rectangular beveled front 7 of the frame is a raised portion or shoulder 12. Between the edges 9 and 10 surrounding the central opening of the frame and the shoulder 12 is a flat area or depression 13 in which is seated an open rectangular lattice like detachable lid 14, the outer edges 15 of which abut against the inner edges of the shoulder 12.

The shanks 16 of a pair of rivets extend in spaced relation to each other through the shoulder 12 on the bottom of the register frame and are secured to the under side of said frame in the usual manner. A portion 100

of the round head 17 abuts against the face of the shoulder and the remaining portion projects over the depression 13, thereby leaving a space between the bottom of the depression and the flat under side of the rivet head to receive and secure the bottom edge of the lid 14 in detachable position within the depression 13 and in abutting relation to the shoulder 12.

10 A pair of rotatable holdfast devices designated generally at 18 are mounted in spaced relation to each other on the shoulder 12, at the top of the register frame. The shank 19 of the holdfast device extends through the shoulder and terminates in a flat head 20 by reason of which the rivet is secured to the under side of the register frame. A round head 21 provided with a slot 22 extending across the head, is eccentrically mounted on the rivet shank 19. The head is adapted to be rotated by a screw-driver inserted in the slot. The eccentric mounting of the head causes its flat under side to project over the depression 13 to secure the lid 14 therein when rotated in one position, while rotated to the opposite position the head is free of the depression and the lid may be detached from the register frame.

15 The detachable lid 14 includes a substantially rectangular rim 23 extending around the central opening of the lid. The central opening of the lid communicates with the openings in the register frame and the hood. A lattice 24 extends over the opening and is 20 secured to the rim 23, except for a rectangular space 25 left free of the lattice at the top thereof for the purpose hereafter referred to. The outer portion of the rim 23 being flat is seated in the depression 13, and the edges 25 15 abut the shoulder 12 and fit under the rivet heads 17 on the front 7 of the register frame. When the lid is seated in the depression the eccentrically mounted heads 21 of the holdfast devices 18 are rotated until they project 30 over the edges 15 of the rim and detachably secure the lid in position. On the inner edge of the rim 23 adjacent the central opening is an outwardly projecting flange 26 extending at right angles to the rim 23. A rod 27" is 35 supported in the aligned apertures 27' in the walls of the flanges 26 at the opposite sides of the central opening and in close proximity to the top thereof, whereby the said rod extends across the central opening in the lid, 40 at the rear of the lattice 24.

45 The valve or damper designated generally at 27 is formed of sheet copper or other suitable non-corrosive metal. The valve or damper comprises a body portion in the form 50 of a hollow substantially rectangular shaped receptacle of such dimensions as will substantially close the openings in the lid, the register frame and the opening in the hood, so as to make the same movable in the opening 55 without binding therein. The dimensions of

the damper or valve should also be such as to allow it to swing freely in the hood 5. The hollow receptacle or damper has solid front and rear walls 28, 29 and solid end walls 30, 31 and a solid bottom wall 32 angularly disposed with respect to the side walls. All of the walls are connected together and spaced from each other.

70 The top of the receptacle or damper is open and the end and front walls adjacent the opening curve outwardly, extending through the opening 25 in the lattice of the lid to form the spout 33 to receive the water or other humidifying medium. The top edge of the rear wall is folded at 34 around the rod 27" and is pivotally supported in position thereby. Extending longitudinally across the inside of the front wall 29 at the top thereof and near the outer edge of the spout 33 is a rod 35 supported on a pair of hooks 75 36 which are secured to the walls of the spout in spaced longitudinal alignment with each other. The rod 35 passes through the hem 36' formed on the top edge of a substantially rectangular shaped piece of absorbent fabric 37. 80 When the rod 35 is supported on the hooks 36 the fabric is positioned thereon between the hooks. The fabric 37 extends down the inside of the front wall 29 of the damper or receptacle 27, having a weighted lower end 38 resting in the acute angled front corner 39 of the bottom. The fabric absorbs the water or other humidifying medium by capillary attraction and when in a heated condition the water evaporates more readily from the fabric than it would otherwise evaporate in the receptacle or damper.

90 The receptacle or damper 27 is pivoted at the top of the lid and is adapted to be adjusted in angular positions across the path of the heat coming out of the hood. A link 40 is secured centrally to the front wall 29 near the lower outer corner of the damper, and projects through an opening 41 at the rear end of flat strip of metal 42. The strip 42 95 is provided with notches 43 on its bottom edge adapted to engage the edge 44 of one of the lattice formations on the lower end of the lid for supporting the damper at any desired open position. To close the damper the strip is raised free of the edge of the lattice and swung around parallel to the face of the lid and slid into the spring clip 45 which is secured to the lower corner of the lid. The link 40 provides a swivel connection for the strip 42 when it is extended angularly or in parallel relation to the damper, which positions the strip assumes when the damper is 100 in the open and shut positions.

110 What I claim is:—

115 1. A damper for a register having an adjustably mounted body portion providing a receptacle for a humidifying agent, said receptacle open at its top.

120 2. A damper for a register having a body

portion providing a receptacle for a humidifying agent, said receptacle open at its top and having the upper portion of its front and end walls projected forwardly.

5. A damper for a register having a body portion providing a receptacle for a humidifying agent, and means for pivotally suspending the receptacle from the upper end of the back thereof.

10. 4. A damper for a register having a body portion providing a receptacle for a humidifying agent, said receptacle open at its top, and means for pivotally suspending the receptacle from the upper end of the back thereof.

15. 5. A damper for a register having a body portion providing a receptacle for a humidifying agent, said receptacle open at its top and having the upper portion of its front and end walls projected forwardly, and means for pivotally suspending the receptacle from the upper end of the back thereof.

20. 6. A damper for a register having a body portion providing a receptacle for a humidifying agent, said receptacle open at its top, and means pivotally connected at the lower end of the front of the receptacle for adjusting the position thereof.

25. 7. A damper for a register having a body portion providing a receptacle for a humidifying agent, said receptacle open at its top and having the upper portion of its front and end walls projected forwardly, and means pivotally connected at the lower end of the front of the receptacle for adjusting the position thereof.

30. 8. A damper for a register having a body portion providing a receptacle for a humidifying agent, and means for pivotally suspending the receptacle from the upper end of the back thereof, and means pivotally connected at the lower end of the front of the receptacle for adjusting the position thereof.

35. 9. A damper for a register having an adjustably mounted body portion providing a receptacle for a humidifying agent, said receptacle open at its top, and a flexible element arranged within the receptacle and possessing capillary characteristics.

40. 10. A damper for a register having a body portion providing a receptacle for a humidifying agent, said receptacle open at its top and having the upper portion of its front and end walls projected forwardly, and a flexible element arranged within the receptacle and possessing capillary characteristics.

45. 11. A damper for a register having a body portion providing a receptacle for a humidifying agent, and means for pivotally suspending the receptacle from the upper end of the back thereof, and a flexible element arranged within the receptacle and possessing capillary characteristics.

50. 12. In combination a hot air register lid, 70 a damper providing a receptacle for a hu-

midifying agent, means pivotally connecting the upper end of the receptacle at the rear thereof to and within the lid, a shiftable member pivotally connected to the receptacle at the lower end thereof for adjusting the position thereof, said shiftable member and lid having coacting means for retaining said member in shifted position and said receptacle having an open top.

75. 13. In combination a hot air register lid, a damper providing a receptacle for a humidifying agent, means pivotally connecting the upper end of the receptacle at the rear thereof to and within the lid, a shiftable member pivotally connected to the receptacle at the lower end thereof for adjusting the position thereof, said shiftable member and lid having coacting means for retaining said member in shifted position and said receptacle having an open top, and a flexible 80 member arranged within said receptacle and possessing capillary characteristics.

85. In testimony whereof, I affix my signature hereto.
